United States Patent Office

Des. 202,374
Patented Sept. 21, 1965

202,374

CLOTHES WASHER

Donald R. Bowers, Akron, Ohio, assignor to The Hoover Company, North Canton, Ohio, a corporation of Ohio

Filed Oct. 13, 1964, Ser. No. 82,150

Term of patent 14 years

(Cl. D49—1)

Fig. 1

Fig. 4

Fig. 3

The rear and side not shown are substantially plane and unornamented.

The dominant features of my design reside in the portions of the drawing shown in full lines.

I claim:

The ornamental design for a clothes washer, substantially as shown and described.
